UNITED STATES PATENT OFFICE.

CARL T. DANIELS, OF LOS ANGELES, CALIFORNIA.

LOG CABIN CONSTRUCTION.

Application filed May 21, 1926. Serial No. 110,620.

This invention relates to a log cabin construction and its object is the provision of an improved and simplified construction that may be produced economically and with 5 facility, and which will have the appearance of a log cabin.

According to the present invention, I provide for utilizing the natural rounding of the tree for producing the desired appearance, and the manner in which the timber 10 is formed and set up produces this appearance and provides an effective structure for receiving and finishing the siding, doors, windows, and the like.

15 The provisions which I make provide a neat, finished and substantial construction, and the present invention relates particularly to the frame work, that is, the formation and manner of setting up the corner posts, 20 the siding studs, and window and door casings and frames.

The siding itself is preferably of the type more fully disclosed in my co-pending application, Serial No. 32,263 filed May 23, 25 1925, and the construction of my present invention has particular utility with the siding of my foregoing application and is particularly adapted for receiving the same and 30 for forming therewith a log cabin construction which is substantial and of pleasing appearance.

The invention is illustrated in the accompanying drawings, in which:—

Figure 1 is a fragmentary horizontal and 35 more or less diagrammatic section showing an embodiment of the present invention;

Figure 2 is a fragmentary inside elevational view of the same;

Figure 3 is a fragmentary perspective 40 view showing the corner construction;

Figure 4 is a vertical section taken on the line 4—4 of Figure 2;

Figure 5 is a detail fragmentary horizontal section through one of the exterior wall 45 jambs; and

Figure 6 is a detail fragmentary horizontal section through one of the inner partition wall jambs.

Referring to the drawings, the structure 50 is shown as having suitable underlying sill members 5 conveniently of four inch by four inch material, although this may, of course, be varied. The floor joists 6, conveniently of two by six material, for example, overlie the sill members 5 and are laid and suitably secured as stretchers there across. The

flooring 7 is laid across and suitably secured to the floor joists 6, and the boards making up the flooring 7 may have tongue and groove engagement, as shown. 60

Mounted in upright position upon the flooring 7, one at each of the corners thereof, are the upright posts 8. These posts 8 are quarter cut in section with the sides 9 and 10 finished substantially square or at right 65 angles to each other and with the natural rounding of the tree at 12 presented internally to the room and giving an interior log appearance at each corner. The finished sides 9 and 10 are disposed flush with the 70 corners of the flooring 7 formed by the edges 13 and 14 as they meet at substantially right angles, and these sides 9 and 10 are presented outwardly and form a mounting for the corner boards or members 15. 75

The external corner members or boards 15 are of substantially half segment formation with finished sides 16 and 17 at substantially right angles to each other, and with the natural rounding of the tree forming the side 80 18. The side 16 is of greater length than the side 17, and this side 16 of greater length is mounted upon one of the finished outer sides of the post 8 with the edge 19 at the corner 20 of the post 8. A similar corner 85 member 15 is similarly mounted upon the other finished side of the post 8 with its edge 19 meeting the edge 19 of the first corner member 15 and with its naturally rounded side presented outwardly. 90

A naturally rounded two-piece corner is thereby presented, giving the appearance externally of a single naturally rounded solid log at the corner. The side 16 of the external corner member 15 is of less length 95 than the adjacent sides 9, 10, of the internal corner post 8 which leaves the inner margins of the sides 9, 10 of the post 8 for receiving the ends of the siding members or boards 25, which are suitably attached thereto. At the same time the sides 17 of the corner members 15 extend out along the ends of the siding members covering said ends and with the rounded sides 18 finishing the corners and giving a complete natural log-like 105 appearance.

The siding members 25 have flat back sides 110, the ends of which are suitably secured externally upon the sides 16, 17 of the inner corner posts 8. The natural rounding of the tree may form the outer sides 27, this natural rounding, as with the other natural-

ly rounded sides, being of log-like appearance and giving the appearance that the cabin is formed of whole natural logs. A single integral tongue 28 along one edge of each board 25, has a back surface continuous with and in the plane of the back side 26 of the board, and a parallel outer surface 29, set in from the rounded outer side 27, forming an outwardly opening mortise 10 to receive a single integral tongue 30 along the opposite edge of each board. The tongues 30 are staggered outwardly from the tongues 28 to form rearwardly or inwardly opening mortises for the reception of the 15 tongues 28. The tongues 30 are disposed adjacent the outer naturally rounded sides 27 with their outer surfaces exposed directly outwardly and rounded to form integral filler strips between the rounded outer sides 27 20 of the boards 25. The back sides of the tongues 30 are parallel with the back sides of the boards 25 and overlap the tongues 28, and fit tightly between and bridge the joints between the boards when a plurality of the 25 boards are assembled.

The boards 25 are shown laid up horizontally as stretchers across the corner posts 8, and between the posts 8 internal vertical studs 35 are provided to which the siding 30 boards may be secured or attached within their lengths. The sides 36 of the studs 35, to which the siding 25 is secured, may be finished flat, as shown, with the natural rounding of the tree forming the inner sides 38 and presented inwardly to give the appearance internally of solid log studs.

Where the interior of the cabin is divided by partitions 40 into rooms, the ends of the partitions 40 may be secured to the sides of 40 the cabin through corner members 42, similar to the corner members 15. The naturally rounded sides 43, of the corner members 42, are presented inwardly and give a natural log appearance at the corners of the inside of the room. The sides 44, 45 of the corner members 42 are finished off flat and at generally right angles to each other, with one side 45 presented to the siding 25, and the other side 44 to the adjacent partition, 50 or one side is presented to one partition and the other side to the other partition at right angles thereto. At the side of the cabin the end of the partition is secured between two corner members 44. The opposite end of the 55 partition is likewise secured between two corner members 42, and the partition at right angles thereto is secured between these two corner members, and a third similar corner member, having its flat side presented to 60 the flat sides of the first two corner members and to the adjacent end of the partition 40, secured therebetween. This further gives a solid post or log-like appearance internally 65 and provides a firm, substantial construction of finished and neat appearance.

Vertical studs 50 may be provided within the lengths of the partitions 40, as desired. These vertical studs 50 have flat outer surfaces to which the partitions are attached, and again the natural rounding of the tree 70 forms the rounded inwardly presented log-like sides 52.

Where a window is desired, a stud 35 is arranged on each side of the window opening on the inside of the cabin. The window 75 opening itself is defined by the inner flat sides of a pair of casing members 56, having flat sides at substantially right angles to the window opening defining sides, and presented to the siding 25, and naturally rounded sides 58 presented inwardly when the casing members 56 are mounted against the studs 35, as shown. The siding boards 25 terminate short of the inner ends of the 80 casing members 56 to provide for the accommodation of stop strips 60, which hold the window frame 62 in place. The bottom of the window opening has a sill 63. The siding beneath the sill 63 is finished on the inside by a right angled corner rounded side 90 casing member 65. The top of the window on the inside is finished by a similar casing member 66.

A door 68 is shown in one of the inner partitions 40. The ends of the partitions 95 40 adjacent the door opening terminate short of the opposite sides thereof, and adjacent each end a pair of casing members 70 are mounted on opposite sides of the partitions. These casing members 70 have their longer 100 flat sides presented to the partitions, their shorter flat sides defining the opening and extending beyond the adjacent ends of the partitions 40, and their naturally rounded sides presented inwardly. Stop strips 72 mounted between the casing members 70 at the door opening ends of the partitions extend beyond the ends of the casing members 105 and form suitable stops for the door 68, which is hinged at 75 to one of the casing members 70.

The exterior wall jamb of Figure 5 is substantially like that described in connection with the interior or partition jamb. In this case, the siding boards 25 are shown as laid upon and secured to the casing members 70' with the stop strip 78 in the corner between the casing members 70' and the siding 25 and the door 75 hinged to the casing members 70', as before.

The top of the structure may be provided with plates 80 and the rafters 82, which may be of two by four timber, may be laid up, as shown, in Figure 4. The partitions 40 may be of one by eight red wood shiplap.

I claim:

1. In a log cabin construction, the combination of an upright inner corner post of quarter cut section and having flat sides at substantially right angles to each other and 130

- presented outwardly, and a naturally quarter rounded side presented inwardly, a pair of outer corner members of half segment section each having flat sides at substantially 5 right angles to each other and naturally rounded sides presented outwardly, one of said corner members being secured with one of its flat sides upon one of the flat sides of the corner post and with one edge of its 10 rounded side at the corner formed by the meeting right angle sides of the corner post, the other of said corner members being secured with one of its flat sides upon the other flat side of the corner post, and with one 15 edge of its rounded side meeting the edge of the other corner member at the corner of the post formed by the meeting right angle sides thereof, and imparting with said first corner member a continuous rounded and 20 solid log-like appearance externally at the corner of the cabin, and the other flat sides of the corner members being disposed normal to the adjacent flat sides of the corner posts and forming right angle 25 depressions therewith.
2. In combination, a corner post of quarter cut section having sides at substantially right angles to each other and a generally rounded side, a pair of corner members each 30 of half segment section and each having flat sides at substantially right angles to each other, one of said corner members being secured to each of the flat sides of the corner post with the edges of their rounded sides 35 meeting at the corner formed by the meeting right angle sides of the post, one of the flat sides of each of said corner members
- being disposed upon each of the flat sides of the post member and the other flat side of each corner member being disposed at substantially right angles to the adjacent flat side of the post member and forming a right angle depression therewith.
3. In combination, a pair of external corner members having naturally rounded sides 40 presented outwardly and meeting edges giving a continuous rounded appearance externally and forming an angular pocket, and a corner post having an angular corner fitting in the angular pocket formed by said corner members and having a naturally rounded side presented inwardly and with said corner members giving the appearance of a solid log, said external corner members having flat sides substantially normal to the 45 flat sides of the corner post and forming right angle depressions therewith.
4. In combination, a pair of external corner members having naturally rounded sides 50 presented outwardly, and meeting edges giving a continuous rounded appearance externally and forming an angular pocket, a corner post having an angular corner fitting in the angular pocket formed by said corner members, said corner post having side extensions and a naturally rounded side presented inwardly and with said corner members giving the appearance of a solid log, and said external corner members having flat 55 sides substantially normal to the adjacent side extensions of the corner post.

In witness whereof, I hereunto subscribe my name this 14 day of May, 1926.

CARL T. DANIELS.
